(57) **CLAIM**

I claim the ornamental design for an adjustable receptacle for pet foods and beverages, as shown and described.

DESCRIPTION

FIG. 1 is a perspective view of an adjustable receptacle for pet foods and beverages, according to my new design;

FIG. 2 is a side elevation view thereof;

FIG. 3 is an opposite side elevation view thereof;

FIG. 4 is an end elevation view thereof;

FIG. 5 is an opposite end elevation view thereof;

FIG. 6 is a top plan view thereof; and,

FIG. 7 is a bottom view thereof.

The broken lines shown in FIG. 7 depict unclaimed features of the receptacle, shown for purposes of illustration, that form no part of the claimed design.
